UNITED STATES PATENT OFFICE.

CHARLES T. SCHOEN, OF PHILADELPHIA, PENNSYLVANIA.

ART OF MANUFACTURING FORGED CAR-WHEELS.

No. 806,580.

Specification of Letters Patent.

Patented Dec. 5, 1905.

Application filed February 21, 1905. Serial No. 246,739.

To all whom it may concern:

Be it known that I, CHARLES T. SCHOEN, a citizen of the United States, residing at Philadelphia, in the county of Philadelphia and State of Pennsylvania, have invented a certain new and useful Improvement in the Art of Manufacturing Forged Car - Wheels, of which the following is a full, clear, and exact description.

10 The object of this invention is to produce a wrought car-wheel.

A flat slab of metal of appropriate size and thickness is produced by rolling out an ingot, and care being taken to remove all portions containing pipings and other defects that may not be cured by the subsequent forging and rolling an angular or circular blank is cut from the slab and subjected to the action of dies, whereby the hub, web, and rim are formed in embryo. Under this treatment the blank is enlarged in an irregular manner and then is sheared to approximate wheel-diameter. The thus sheared blank is subjected to pressure in dies, whereby the hub and adjacent portions of the rim are substantially finished and the flanged rim produced. The blank is then subjected to the action of rolls which stretch the web radially and reduce and finish it and the tread and flange, and thereafter the wheel is dished or coned and its rim rounded or trued in any approved way.

In the accompanying drawings, illustrating the invention, in the several figures of which like parts are similarly designated, Figure 1 is an edge elevation of a circular or angular blank, and Figs. 2, 3, 4, and 5 are central cross-sections representing the successive steps in the formation of the wheel. Fig. 6 is a composite cross-section composed of the parts shown in Figs. 1, 2, 3, 4, and 5, and it is designed to illustrate the changes in contour and diameter in transforming the blank of Fig. 1 into the finished dished or coned wheel of Fig. 5.

15 The presence of pipings or other defects in a car-wheel are soon developed by use, and any such defects in a blank from which a wrought car - wheel is produced cannot be cured by the forging or rolling operations to which it is subjected in the manufacture of such wheels. It is therefore necessary to select a blank that is free from all such defects. If an ingot be rolled into a strip about four

and three-quarters inches thick by twenty- 55 seven inches wide and of indefinite length, the pipings or segregations which originally occur in the top of the ingot will appear in the forward end of the strip when it is rolled down, and hence this forward end may be cut 60 off until only solid metal is reached. From this solid metal is cut a slab of suitable dimensions to form a wheel of the desired diameter. This slab may be reduced by forging to a circular body or it may be taken in 65 its rectangular shape and in either instance subjected to the action of dies. Suppose the slab 1 to be of the relative proportions shown in Fig. 1. The first-operation dies will shape this slab, as indicated in Fig. 2, so as to make 70 in embryo the hub 2, web 3, and rim 4, leaving a diaphragm 5 of metal within the hub. The product of the first-operation dies (shown in Fig. 2) has its rim sheared, and the shear is represented by the lines 6. It may be noted 75 here that the shears descend in the direction of the arrow, Fig. 2, and the product shown in Fig. 2 is inverted in the view, so as to make its center lines conform to the center lines of the other figures. The shear is ef- 80 fected while the product is still in the dies. This product, Fig. 2, is then subjected to the action of other dies, whereby the hub 7 is formed and also the portion 8 of the web ad- 85 jacent the hub, and the web is reduced in thickness, and the metal at 4, Fig. 2, is brought into the shape of a rudimentary rim 9 and flange 10. At the conclusion of this opera- 90 tion the diaphragm 5 may be punched out of the hub, so that the hub is practically com- 95 pleted. The product of Fig. 3 is then sub- jected to the action of rolls which further re- duce the web 11 and extend it radially and finish the inner surfaces 12 and 13 of the rim, while other rolls finish the flange 14 and tread 15, all as shown in Fig. 4. The product of Fig. 4 is then ready for the dishing or coning operation, as shown in Fig. 5.

As shown in Fig. 6, the first operation trans- 100 forms the blank in every direction, increasing its thickness at the hub and decreasing it in thickness in the web and rim and stretching it radially, and the next operation further re- 105 duces the web portion in thickness and widens out the rim portion in addition to shaping it, and the next operation further reduces and finishes the web and increases the blank radially to finished size, maintaining the width of

rim, while decreasing its thickness and drawing out the flange. Any defect in the metal will be discovered in the first operation as a rule, and the blank may be discarded at that point, so that the risk of producing defective wheels is reduced practically to a minimum. Any defects in the blank that may be cured by the welding action of the dies will be rectified by the successive forging operations to 10 which the blank is subjected.

Of course the blank is heated in the first instance and reheated as often thereafter as is necessary, although it is possible by the use of expeditious transferring machinery to perform the three die operations represented in 15 Figs. 2, 3, and 4 in one heat.

Any irregularity or unevenness in the tread may be corrected by a suitable rounding apparatus, such as dies or a milling-machine.

What I claim is—

The art of manufacturing forged car-wheels consisting in producing a slab of wrought metal practically free of pipings and other structural defects, heating it, die-forming thereon a rudimentary hub, web and tread, shearing the rim, next finishing the hub and the adjacent web and shaping the rim in dies, and then reducing the web and extending it radially to the proper diameter and finishing the tread and flange by rolling.

In testimony whereof I have hereunto set my hand this 17th day of February, A. D. 1905.

CHARLES T. SCHOEN.

Correction in Letters Patent No. 806,580.

I* is hereby certified that in Letters Patent No. 806,580, granted December 5, 1905, upon the application of Charles T. Schoen, of Philadelphia, Pennsylvania, for an improvement in the "Art of Manufacturing Forged Car-Wheels," an error appears in the printed specification requiring correction, as follows: On page 2, line 25, the word "thereon" should read *thereof*; and that the said Letters Patent should be read with this correction therein that the same may conform to the record of the case in the Patent Office.

Signed and sealed this 19th day of December, A. D., 1905.
